UNITED STATES PATENT OFFICE.

EDWIN DARBY, OF IOWA CITY, IOWA, ASSIGNOR OF ONE-HALF TO
BENJAMIN J. HARDY, OF IOWA CITY, IOWA.

CRUDE-OIL BURNER.

No. 814,360.

Specification of Letters Patent.

Patented March 6, 1906.

Application filed December 8, 1903. Renewed July 6, 1905. Serial No. 268,556.

To all whom it may concern:

Be it known that I, EDWIN DARBY, a citizen of the United States, residing at Iowa City, in the county of Johnson and State of Iowa, 5 have invented a new and useful Crude-Oil Burner, of which the following is a specification.

This invention relates generally to oil-burners, and more particularly to that class thereof known as "retort - vaporizers," and in which the oil is not only thoroughly vaporized before being ignited, but is also commingled with a certain amount of superheated air and steam.

15 The object of my invention is to provide a simple and highly efficient form of burner which can be used in either a cooking or heating stove and one which can be used for burning oil in either a crude or refined state.

20 With these objects in view my invention consists, essentially, in the employment of a ring having a plurality of openings, a flash-pan hinged to the ring and adapted to occupy the central opening space in the said ring, a 25 hood adapted to rest above the flash-pan and having a central opening surrounded by a depending collar, said hood being supported by means of a plurality of air-trunks preferably integral with the hood, said trunks intersecting or meeting each other at the center of the 30 hood, an oil-supply pipe leading into the said trunks and hood at the intersection of said trunks, and a water-coil arranged within the hood, the supply end of said pipe projecting upwardly through the hood and the discharge end of said pipe being connected to an oil-supply pipe whereby the steam will be mixed with the oil prior to the mixing of said oil with the air which passes through the air- 35 trunks, the lower ends of said air-trunks resting in the openings produced in the circular ring.

The invention consists also in certain details of construction and novelties of combination, all of which will be fully described 45 hereinafter and pointed out in the claims.

In the drawings forming part of this specification, Figure 1 is a perspective view of an oil - burner constructed in accordance with 50 my invention. Fig. 2 is a vertical sectional view. Fig. 3 is a top plan view of the pan. Fig. 4 is an inverted perspective view of the hood and the air-trunks connected thereto.

Fig. 5 is a detail perspective view of the flash-pan. Fig. 6 is an inverted perspective view 55 of the ring.

In constructing a burner in accordance with my invention I employ a circular ring A, which is adapted to rest upon the grate at the bottom of the stove, or it may be supported in the stove in any other suitable manner. This ring has a plurality of openings B, arranged at regular intervals, there being four such openings shown in the drawings, and said openings are rectangular in shape. A 60 pan C is hinged to the under side of the ring, as shown at C' in Fig. 2, said pan having an outwardly-extending flange C², which engages the under side of the ring, also most clearly shown in Fig. 2. The pan C has a conical-shaped bottom, the apex C³ extending slightly above the sides of the pan and coiled upon the bottom in convolute form is the asbestos wicking D. The pan C is hinged to the ring, so that it can be dropped down for the purpose of cleaning or removing any sediment that might accumulate therein. The hood E, 70 circular in form, is supported above the pan C, said hood having a plurality of hollow air-trunks F integral with the exterior thereof, 80 said air-trunks being essentially right angular in shape, the horizontal members gradually tapering and converging or intersecting at D', and the uprights members of the said air-trunks fit into the openings B produced 85 in the ring A, and thus conveying the air from the bottom of the stove to the center of the oil-burner. The hood E has a central opening E', which is located at the conjunction or intersection of the air-trunks, said opening 90 being surrounded by a depending collar E², said collar tapering or being contracted, the contracted end thereof being arranged adjacent the apex of the conical bottom. A 95 water-pipe G passes through the top of the hood and is coiled several times in a convolute form the coils of the pipe resting directly beneath the hood, and the discharge end G' of said pipe is connected to the oil-supply pipe H by means of the union H', the delivery 100 end of the oil-pipe passing into the air-trunks at their intersection or conjunction.

From the foregoing description, taken in connection with the accompanying drawings, it will be understood that the oil is first fed 105 through the pipe H and drops upon the con-

ical bottom of the flash-pan and is absorbed by the asbestos wicking. This oil is ignited and the water vaporized, the water passing through the coil-pipe G, arranged in the hood, 5 and the steam passes upwardly and mingles with the oil, which continues to flow through the pipe H. In the meantime the air is being drawn through the air-trunks and commingles with the mixed oil and steam, thereby 10 producing a fuel-vapor, which becomes ignited at the central opening of the hood and produces an intense heat.

The burner is constructed in such manner that there are no parts likely to get out of order and the commingling of the air, oil, vapor, 15 and steam is accomplished in an easy and convenient manner at the proper time.

Having thus fully described my invention, what I claim as new, and desire to secure by 20 Letters Patent, is—

1. An oil-burner comprising a pan, a hood having integral air-trunks by means of which the said hood is supported, said air-trunks communicating with the central opening in 25 the hood, the oil-pipe leading into the air-trunks, the water-pipe arranged between the hood and pan, and connected with the oil-pipe, as set forth.

2. An oil-burner comprising a pan, a ring 30 surrounding the said pan and having a plurality of openings, a hood having integral air-trunks, the depending legs of which fit into the openings in the ring, the horizontal portions of said air-trunks converging at the center of 35 the hood, said hood having an opening at the convergents of the air-trunks, and the water-pipe arranged within said hood and connect-

ed with the oil-pipe leading into the air-trunk, as set forth.

3. An oil-burner comprising a ring having 40 a plurality of openings, a pan hinged to the said ring and having a conical-shaped bottom, a hood having a plurality of air-trunks, the depending legs of which are adapted to fit into the openings in the rings, the horizontal 45 members of said air-trunks converging at the center of the hood, said hood having a central opening surrounded by a depending collar, and the water-pipes arranged within said hood and connected with the oil-pipe as set 50 forth.

4. An oil-burner comprising a ring having a plurality of openings, a pan hinged to said ring and having a conical bottom, a hood having the air-trunks integral therewith the depending legs of said air-trunks fitting in the 55 openings in the ring, the horizontal members of said air-trunks converging at the center of the hood, said hood having a central opening, said opening being surrounded by a depending collar which collar tapers toward the apex of the conical bottom, an oil-pipe leading into the air-trunks at their conjunction or intersection, a water-pipe passing through the top of the hood and coiled beneath the hood, the 60 discharge end of said water-pipe being connected to the oil-pipe, and asbestos wicking arranged upon the conical-shaped bottom of the pan, as set forth.

EDWIN DARBY.
